ILLUMINATED HANDLE FOR REFRIGERATED CABINET DOORS

John J. Voda, Evansville, Ind., assignor to International Harvester Company, a corporation of New Jersey

Application October 28, 1950, Serial No. 192,747

2 Claims. (Cl. 240—4)

1

This invention relates generally to illuminating devices and more particularly to illuminating devices for use in refrigerated cabinets.

Of the many designs of low temperature refrigerated cabinets, commonly termed freezer cabinets, which have been introduced to the public for domestic use, the horizontal type cabinet seems to have been more generally accepted. Since the freezer cabinet is commonly used for the storage of a variety of foods, it is desirable that some means be provided for illuminating the food storage compartment in order that the user may select the package of food he wishes to remove. This is particularly true when the freezer cabinet is positioned in a dark room or basement. The horizontal type freezer cabinet, commonly termed freezer chest, is usually provided with a horizontally disposed door which pivots upwardly in order to allow access to the storage compartment. Since the packages of food in many instances will be stacked to the very top edge of the food storage compartment, it has been found that a desirable location for an illuminating lamp is in the door. In this arrangement, the lamp will not be covered or damaged by the food packages and will illuminate the interior of the cabinet regardless of how high the food packages are stacked.

An object of the present invention is to provide a cabinet with illuminating means which will not be covered or damaged by articles stored in the cabinet.

Another object of the invention is to position a lamp on the door of a cabinet which will illuminate the interior of the cabinet when the door is open.

A further object of the invention is to provide a cabinet door with a hollow handle having a lamp secured therein, whereby the handle serves as a shield and reflector for the lamp.

A still further object of the invention is to provide a cabinet with an illuminating device which is easily installed, requires few parts and can be easily reached for servicing.

Other objects and advantages of the invention will be appreciated by those skilled in the art as the invention becomes better understood by reference to the following description when considered in connection with the accompanying drawings, in which:

Fig. 1 is a vertical sectional view of a horizontal type refrigerated cabinet in which the invention is incorporated.

Fig. 2 is a rear elevational view of the door handle and illuminating means taken on line 2—2 of Fig. 1.

Fig. 3 is a sectional view of the handle and illuminating means taken on line 3—3 of Fig. 2.

Referring to the drawings for a detailed description of the invention, a freezer chest is represented generally by reference number 10. The cabinet 10 comprises a decorative or outer shell 11 mounted upon a base 12. Spaced within the outer shell is an inner liner 13, the walls of which enclose a food storage compartment 14 having an open top which provides access thereto. Insulating material 15 fills the space between the outer shell 11 and inner liner 13 in order to reduce heat transfer therebetween. An evaporator coil 44 is wrapped around the inner liner 13 and secured thereto by clamp member 45. Refrigerant is passed through evaporator coil 44 which cools the walls of the inner liner 13 and maintains the temperature of the food storage compartment 14 at approximately 0° F.

20 A door 16 is secured to the back of the cabinet by hinges 19. Door 16 comprises an inner door panel 17 secured to an outer door pan 18 with insulation 19 therebetween. A rubber gasket 20 is positioned around the periphery of the door 25 which seals around the food compartment 14 when the door 16 is horizontally disposed. A handle 21 is secured to the front edge 48 of the door 16. In opening the door 16, the operator may grasp the lower edge 22 of the handle and swing the door upwardly until it reaches a substantially vertical position. With the door in this position, the operator will have easy access to the food storage compartment 14 and may reach therein and remove any item therefrom. The handle 21 may be provided with latching means, if needed, and the door may be equipped with counterbalancing means.

The handle 21 is substantially rectangularly shaped and is hollow with front portion 23 being 40 radially curved and side portions 24 and 25 perpendicular thereto. The lower edge 22 is rounded in order to provide a smooth surface for the operator to grip. On the back side of front portion 23 is formed a strengthening rib 26 which 45 is perpendicular to front portion 23 and comprises two vertical portions 27 and 28 connected by a longitudinal portion 29. A mounting plate 30 is secured to the handle by screws 31 and is provided with three lots 32 through which 50 mounting screws extend and secure the handle 21 to the front edge 48 of the door 16.

A horizontally disposed rib 47 is formed on the back side of front portion 23 which extends between rib portion 28 and side 25. The rib 47 is 55 provided with a circular shaped slot 46 into which a rubber encased electric lamp socket 33

is secured. The socket 33 is provided with an annular groove 34 bordered on each side by annular rib 35 and annular rib 36. The annular groove 34 fits into circular slot 46 and the annular ribs 35 and 36 grip the rib 47 and hold the socket 33 securely in place.

An electric cord 37 supplies current to the socket 33 and an elongated electric lamp 38 fits in said socket and extends vertically between rib 28 and side 25. A slot 43 is provided in the upper portion of rib 28 through which the cord 37 passes and is connected to an electric switch 39. The electric switch is one of the many types on the market today which has a spring pressed plunger 40 for making and breaking the circuit or, if desired, may be a mercury switch which is operated by the movement of the door. The switch is secured to the handle 21 by screws 41 with the plunger 40 extending toward the cabinet 10. An electric cord 42 connects the switch 39 to a suitable electric supply source.

When the door 16 is in the horizontal or closed position as shown in Fig. 3, the plunger 40 will contact the outer shell 11 and be forced inwardly which opens the switch contacts and breaks the circuit to the lamp 38. As the door 16 is swung upwardly to open position as shown in Fig. 1, the plunger 40 will clear the outer shell 11 and the spring pressed plunger will automatically move outwardly. The switch contacts will be closed and the circuit to lamp 38 will be completed.

A substantial portion of handle 21 extends below the inner door panel 17. Lamp 38 is positioned in relation to the door so that it also extends below the inner door panel 17. The rear side of the handle 21 is polished to a high luster or painted a light color in order that it will act as a reflector and direct the rays of light from electric lamp 38 into the food storage compartment 14. Since the front portion 23 of handle 21 extends below lamp 38, it will also act as a shield for protecting the lamp 38 and for preventing the light rays emitted by the lamp from striking the operator's eyes.

From the foregoing it will be apparent that an illuminating device is provided which automatically illuminates the food storage compartment 14 when the door 16 is opened. The structure requires few parts and is economical since the door handle 21 is utilized to act as a shield and reflector for the bulb 38 which eliminates the necessity for a separate shield and reflector. The food storage compartment 14 can be completely filled with food and still be adequately illuminated by the electric lamp 38. With the lamp 38 and switch 39 positioned in the handle 21, access to both is provided when the door 16 is open, which provides a structure which is easy to assemble and can be easily reached for servicing.

In the illustrated embodiment, the illuminating device is shown incorporated in a freezer chest. Since the device is applicable to receptacles of various kinds, it is not intended that it be limited to use with a freezer chest. It is to be understood that numerous changes and modi-

fications may be made in the form, construction and arrangements of elements embodying my invention, and therefore, the forms thereof shown in the drawings and described above are intended to be illustrative and are not intended to limit the scope of the following claims.

What is claimed is:

1. In combination with a door pivotally secured to a refrigerated cabinet, a handle having a curved front wall and a first end wall and a second end wall which extend substantially perpendicular to said front wall, strengthening ribs formed on the rear side of said front portion between said end walls, a mounting rib extending between said first end wall and one of said strengthening ribs, said mounting rib being provided with a slot, an electric socket having a groove therein which is received by said slot, an elongated lamp secured in said socket and positioned between said first end wall and said strengthening ribs, and a mounting plate fastened to said front portion between said strengthening ribs, said handle being secured by said mounting plate to the front edge of said door with said lamp and front portion extending past the inner surface of said door, said handle acting as a shield and reflector whereby the rays of light from the lamp are directed into the interior of the cabinet.

2. In combination with a door pivotally secured to a refrigerated cabinet, a handle having a curved front wall and a first end wall and a second end wall which extend substantially perpendicular to said front wall, strengthening ribs formed on the rear side of said front portion between said end walls, a mounting rib extending between said first end wall and one of said strengthening ribs, said mounting rib being provided with a slot, an electric socket having a groove therein which is received by said slot, an elongated lamp secured in said socket and positioned between said first end wall and said strengthening ribs, a mounting plate fastened to said front portion between said strengthening ribs, said handle being secured by said mounting plate to the front edge of said door with said lamp and front portion extending past the inner surface of said door, said handle acting as a shield and reflector whereby the rays of light from the lamp are directed into the interior of the cabinet, and an electric switch fastened to the rear side of said front portion which closes a circuit to said lamp when the door is opened and opens said circuit when the door is closed.

JOHN J. VODA.
